UNITED STATES PATENT OFFICE

171,509

AIRCRAFT

Salvador Lightbourn, Los Angeles, Calif.

Application August 28, 1952, Serial No. 21,226

Term of patent 14 years

(Cl. D71—1)

To all whom it may concern:

Be it known that I, Salvador Lightbourn, a citizen of Mexico, residing at Los Angeles, California, have invented a new, original, and ornamental Design for an Aircraft, of which the following is a specification, reference being had to the accompanying drawings, forming a part hereof.

Figure 1 is a top plan view of an aircraft showing my new design.

Figure 2 is a side elevational view thereof, and Figure 3 is a bottom plan view thereof.

I claim:

The ornamental design for an aircraft, as shown.

SALVADOR LIGHTBOURN.
